UNITED STATES PATENT OFFICE.

ROBERT WALTONN WIEDERWAX, OF ATLANTIC CITY, NEW JERSEY, ASSIGNEE TO
GEIST MANUFACTURING COMPANY, OF ATLANTIC CITY, NEW JERSEY, A CORP.
OF DELAWARE.

FUEL-OIL BURNER.

Application filed November 2, 1922. Serial No. 593,662.

To all whom it may concern:

Be it known that I, ROBERT W. WIEDERWAX, a citizen of the United States, residing at Atlantic City, in the county of Atlantic and State of New Jersey, have invented certain new and useful Improvements in Fuel-Oil Burners, of which the following is a specification.

This invention relates to fuel oil burners, and is an improvement over the construction shown in my copending application filed June 2, 1922, Serial No. 565,339.

In the said application, I have described and claimed a burner for burning the heavier, relatively cheap, fractions of petroleum oils adapted to be used in heating furnaces and in the various industries. Prior to my invention, it has been impossible to burn heavier oils in burners of this character without depositing carbon and creating smoke.

In a copending application filed Nov. 2, 1922, Serial No. 593,693, I have disclosed and claimed a process of burning oil wherein the oil under pressure is heated to a temperature above its normal boiling point to maintain it in liquid form by the pressure and is then projected from a highly heated surface to immediately flash the oil, breaking it up into minute particles and thoroughly vaporizing it. This vapor is then mixed with an aeroform liquid and projected through a burner nozzle.

In the present invention, I provide an apparatus suitable for use in practicing the process disclosed in my said copending application, which is an improvement over the device shown in my prior apparatus application.

In the prior apparatus application, I have shown a burner casing having a main burner placed at the back of the casing, whereby the incoming oil and other fluid such as air or steam may be heated by the heat of the burner in jackets surrounding the casing.

In the present apparatus, I provide a main burner arranged within the casing having its outlet end arranged adjacent the front of the casing and an auxiliary burner having its outlet arranged adjacent the back of the casing to heat the oil retort and the fluid preheating chamber surrounding the burner casing.

In the accompanying drawings, I have

shown one embodiment of the invention. In this showing:

Figure 1 is a central longitudinal sectional view through a burner,

Figure 2 is a similar view of the main burner pipe and auxiliary burner pipe with the casing removed, and,

Figure 3 is a transverse sectional view on line 3-3 of Figure 2.

Referring to the drawings, the reference numeral 1 designates a furnace wall forming a part of the furnace chamber in which the burner is to be used. The burner casing consists of a cylindrical shell 2 formed of any suitable metal, which is open at each end and is provided with a flange 3 at its forward end. The forward portion of the casing is surrounded by a cylindrical member 4, forming a space 5 for preheating air or steam. The front end of this member is connected to the flange 3 in any suitable manner as by welding. The rear of the casing is surrounded by a similar cylindrical member 6, spaced therefrom to form an oil heating retort 7. The members 4 and 6 are provided with flanges 8 and 9, respectively, at their adjacent ends, which form end walls and are secured to the burner casing in any suitable manner. The rear end of the cylindrical member 6 is inclined downwardly, as at 10, and is provided with a skirt 11 overlying the burner casing and secured thereto in any suitable manner, as by welding. The preheating chamber 5 is provided with an inlet pipe 12 and an outlet pipe 13. The oil retort is similarly provided with an inlet pipe 14 and an outlet pipe 15. The fluid outlet pipe 13 is connected to a valve casing 16, having a valve 17 arranged therein. This valve is provided with an operating handle 18. A burner pipe 19 is arranged within the burner casing. A pipe 20 is connected to the valve casing 16 at one end and the opposite end is connected to the burner pipe by a fitting 21.

As shown, a jet pipe 22 is arranged within the pipe 20 and projects into the burner pipe. The rear end of this pipe is received in a plug 23, arranged in the end of the valve casing, permitting communication between the valve casing and the jet pipe 22 and preventing communication between the valve casing and the pipe 20. The oil outlet pipe 15 is connected to a valve

- casing 24, having a valve (not shown) arranged therein, controlled by a valve handle 25. A pipe 26 forming a part of the fitting 21 is connected to the valve casing. 5 This pipe has a relatively small opening 27, communicating with the interior of the fitting adjacent the jet pipe 22. A nozzle 28 is arranged on the outer end of the burner pipe being connected thereto by a fitting 29. 10 As shown, the outlet end of the nozzle of the main burner pipe is arranged at the front of the burner casing, whereby the flame is projected beyond the burner casing. An auxiliary burner of similar construction 15 is provided for the purpose of heating the oil retort and the fluid preheating chamber. As shown, branch pipes 30 and 31 are connected to the pipes 13 and 15, respectively, the fluid pipe being connected to a valve 20 casing 32, having a valve 33 arranged therein. A pipe 34 is connected to the valve-casing and this pipe is provided with a jet pipe 35, arranged therein. A plug 36 prevents communication between the valve casing and 25 the pipe 34. The end of the jet pipe projects into a burner pipe 37. The auxiliary oil pipe 31 communicates with a valve casing 38 which is in turn connected to a pipe 39, leading into the burner pipe adjacent the 30 jet pipe 35.

In operation, air or steam is delivered to the preheating chamber 5 through pipe 12 and oil is delivered to the retort 7 through pipe 14. The fluid in the preheating chamber 35 is heated to a very high temperature by heat of the auxiliary burner 37. The oil delivered to the retort is under pressure and is heated to a temperature above its normal boiling point but below the boiling point of the oil at the pressure employed. I find it advantageous to heat the oil in the retort to a temperature just below its boiling point at the pressure employed whereby the oil is maintained in a liquid state by the pressure. 40 The preheated fluid passes through the pipe 13 to the valve casing 16, and thence to the jet pipe 22. Passage of the fluid through the jet pipe heats the surface of this pipe to a high temperature. The oil from the 45 retort is projected through the pipe 26 against the surface of the jet pipe and due to the high degree of heat therein, is immediately flashed into vapor form. The projection of the oil against this surface together with the high degree of heat employed, causes a complete breaking up of the oil into minute particles and insures complete vaporization. It will be noted that the oil delivered into the fitting 21 at an angle 50 causes it to flow rearwardly a short distance before it is drawn into the burner pipe which further insures complete admixture of the particles of oil and causes proper vaporization. From the vaporizing chamber, the oil passes into the burner pipe when it is mixed 55

with air or steam at a high temperature, or other fluid capable of supporting combustion and is projected through the nozzle in a flame.

The operation of the auxiliary burner 37 70 is identical to the operation of the main burner. The heat generated by the auxiliary burner heats the retort and preheating the chamber to furnish the properly heated fluid and oil to the main burner. 75

It is to be understood that the form of my invention herewith shown and described is to be taken as a preferred example of the same, and that various changes in the shape, size, and arrangement of parts may be resorted to without departing from the spirit of the invention or the scope of the subjoined claims. 80

I claim:

1. A burner for liquid fuel comprising a 85 burner casing, a burner pipe arranged in said casing, a retort surrounding a portion of said casing, a preheater for fluid surrounding another portion of said casing, con- nections between said burner pipe, said retort and said preheater, an auxiliary burner arranged in said casing, and connections between said auxiliary burner, said retort and said preheater.

2. A burner for liquid fuel comprising a 90 casing, a main burner arranged within said casing, a tubular member surrounding said casing and spaced therefrom to form a retort, a second tubular member surrounding another portion of said casing and spaced 100 therefrom to form a preheater for fluid, pipes connecting said retort and said preheater to said main burner, an auxiliary burner arranged in said casing, and connections between said pipes and said auxiliary 105 burner.

3. In a burner for liquid fuels, a casing having open ends, a burner pipe arranged in said casing, a retort surrounding a portion of said casing, a preheater surrounding another portion of said casing for preheating fluid to be mixed with said fuel, pipes connecting said retort and said preheater to said burner pipe, an auxiliary burner arranged in said casing, and connections between said 110 pipes and said auxiliary burner.

4. In a liquid fuel burner, a casing, a main burner pipe, a fuel heating jacket surrounding a portion of said casing, a jet extending partially through said main burner pipe 120 adapted to receive a highly heated fluid to be admixed with the fuel, a fuel inlet pipe connecting said jacket to said burner pipe intermediate the ends of said burner pipe, and an auxiliary burner arranged in said casing 125 to preheat the fuel in said jacket.

5. A burner for liquid fuels comprising a substantially tubular burner casing having open ends, a retort surrounding a portion of said casing, a preheater surrounding another 130

portion of said casing, a burner pipe arranged in said casing, a jet arranged in said burner pipe, a pipe connecting said jet to said preheater, to deliver heated fluid to said jet, a pipe extending from said burner pipe intermediate the ends of said jet and connected to said retort, an auxiliary burner arranged in said casing, and connections

between said pipes and said auxiliary burner. In testimony whereof, I affix my signature to in presence of two witnesses.

ROBERT WALTONN WIEDERWAX.
